UNITED STATES PATENT OFFICE.

JOHN LEE OEFINGER, OF DENVER, COLORADO.

BROOM HOLDER.

1,423,678.

Specification of Letters Patent. Patented July 25, 1922.

Application filed July 9, 1921. Serial No. 483,561.

To all whom it may concern:

Be it known that I, JOHN LEE OEFINGER, a citizen of the United States, residing in the city and county of Denver and State of Colorado, have invented certain new and useful Improvements in Broom Holders; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to broom holders and has for its object the production of a device of this type that shall be exceedingly simple in construction and still be of a substantial and rugged design.

20 I am aware that various types of broom holders have been made some of which embody, broadly, some of the features that I use, but so far as I am aware, I am the first one to make a holder embodying all of the 25 specific features of construction of my present device.

In order to more clearly describe my invention, reference will be had to the accompanying drawing in which—

30 Fig. 1 shows a plan view of my device.

Fig. 2 shows a side elevation of the same and

Fig. 3 shows my device attached to the wall and supporting a broom.

35 In the drawings the same reference characters refer to the same parts in the several views.

My holder consists of a supporting member 1 which is formed of a reversely bent member one part 2 being provided with a screw threaded portion 3, the other part 4 having the end portion 5 thereof wound around the member 2 just above the threaded portion. The two members 2 and 4 form an 45 enlarged circular opening 6 at their point of

juncture. Secured to the support 1 is a ring 7 having a hooked portion 8 for engagement with the loop 6. Ring 7 has an internal diameter somewhat larger than that of a broom handle.

50

My device is employed as follows:

The holder is fastened to wall 9 by screwing the threaded portion 3 thereof into the surface of the wall until the coiled portion 5 comes into contact therewith, care being 55 taken to adjust the rotary position of the support so that ring 7 will be free to move vertically about its pivot.

The handle 10 of broom 11 is inserted into ring 7 from below. It will be found that 60 when the broom is released it will not slide out of the ring 7 but will be firmly held in its suspended position.

In order to remove the broom, the outer edge of ring 7 is raised and thereby its hold 65 on the broom will be released permitting the broom to be withdrawn.

Although I have described my device as a broom holder it is, of course, evident that it is as well adapted to support any article 70 having a handle like a broom, such, for example, as a mop. It can also be used as a support for handles of various kinds sold in stores, such as handles for hoes, rakes, forks, etc. making a neat and economical way of 75 supporting and displaying these articles.

Having now described my invention what I claim is:

A broom holder consisting of a support which is reversely bent intermediate its ends 80 to form an eye for the support of a ring, one end of said support having a threaded portion, the other end being coiled about the threaded end just above the threaded portion thereof and a wire ring having one end 85 of the wire formed into an eyelet connected to the eye of said support.

In testimony whereof I affix my signature.

JOHN LEE OEFINGER.
